UNITED STATES PATENT OFFICE.

ALONZO G. VAN NOSTRAND, OF BOSTON, MASSACHUSETTS.

DESIGN FOR A FAUCET AND POST FOR THE SAME.

49,320.

Specification for Design.

Patented July 4, 1916.

Application filed June 21, 1915. Serial No. 35,463. Term of patent 14 years.

To all whom it may concern:

Be it known that I, ALONZO G. VAN NOSTRAND, a citizen of the United States, residing at No. 482 Beacon street, Boston, in the county of Suffolk and State of Massachusetts, have invented a new, original, and ornamental Design for Faucets and Posts for the Same, of which the following is a specification, reference being had to the accompanying drawing, forming part thereof.

Figure 1 is a side elevation of the faucet

and ornamental post for the same showing my new design. Fig. 2 is a front elevation of the same.

I claim:

The ornamental design for a faucet and post for the same, as shown.

ALONZO G. VAN NOSTRAND.

Witnesses:

HECTOR M. HOLMES,
ALEX D. SALINGER.
